UNITED STATES PATENT OFFICE.

ALBERT F. DAUM, OF PITTSBURGH, PENNSYLVANIA.

REFILLABLE FUSE.

1,326,481.

Specification of Letters Patent. Patented Dec. 30, 1919.

Application filed April 17, 1916. Serial No. 91,665.

To all whom it may concern:

Be it known that I, ALBERT F. DAUM, a citizen of the United States, residing at Pittsburgh, in the county of Allegheny and State of Pennsylvania, have invented certain new and useful Improvements in Refillable Fuses, of which the following is a specification.

My present invention relates to improvements in refillable fuses.

Fuses of this type for commercial adoption must have certain characteristic features to take care of the many conditions which are encountered in fuse use; some of these conditions are as follows:

The fuse should be of a construction which will permit the removal of the blown fusible element and the insertion of a new element without requiring the use of tools, since it may be necessary to make these changes quickly and at points where tools cannot be conveniently obtained; the construction must be as simple as possible to not only provide for inexpert manipulation but also to permit of manufacture at a minimum cost; a maximum amount of metallic contact with the fusible element is essential in order that the heat produced may be dissipated as rapidly as possible, and also to tend to localize the point of disruption away from the ends of the fuse, thereby preventing damage to the non-fusing elements, thus enabling these parts to be used continuously with the ready manipulation initially employed.

These conditions are met by the invention herein disclosed which in addition provides a number of other features among which are the following:

40 A construction adapted to provide for automatic indication of the blowing of the fuse; providing limited axial movement of the parts when the fuse blows, thereby reducing expansion effects to a material extent; the provision of a simple form of clamping member, either in unitary or built-up construction, and which not only is removably secured to the cap but also co-operates with the cap in producing the clamping action; the use of a clamping member of such form as will co-operate with the shell for certain purposes and in such manner as will permit the co-operating parts of the shell to be formed in a simple and inexpensive manner; the provision of a clamping member which can be readily

60 stamped out; the use of a structure in which the cap can be quickly removed or placed in position; to provide a construction which, when applied to the knife-blade type fuse, will act as a preventive against the use of a fusible element of increased thickness; and to provide a structure which is durable in construction and simple and efficient in operation.

65 To these and other ends, the nature of which will be readily understood as the invention is hereinafter disclosed, said invention consists in the improved construction and combination of parts, hereinafter fully 70 described, illustrated in the accompanying drawings, and more particularly pointed out in the appended claims.

75 In the accompanying drawings, in which similar reference characters indicate similar parts in each of the views,—

Figure 1 is a longitudinal sectional view of a fuse constructed in accordance with my invention; the section being arranged to show the elements or sections taken at right 80 angles to each other.

Figs. 2, 4, 5 and 7 are similar views showing various modifications.

Figs. 3 and 6 are views partly in section and partly in elevation showing other modified forms.

Fig. 8 is a longitudinal sectional view showing another modification.

Fig. 9 is a longitudinal sectional view showing the effect when a fusible element of 90 different thickness is employed.

Fig. 10 is a perspective view of the clamping element shown in Figs. 7 and 9.

Fig. 11 is a perspective view of the clamping element shown in Fig. 8.

Fig. 12 is a diagrammatic view indicating the effect of the use of different thicknesses of fusible element in a fuse of the knife-blade type.

In the present invention, the basic idea 100 is to provide a threaded engagement between the cap and the opposing clamping member (the cap itself forming the other member), such clamping member being held against complete rotation by the shell, thus 105 connecting the cap and inner member as a unitary structure and at the same time practically dispensing with the use of threaded members independent of the cap but connecting the cap and clamping member together. Coupled with this basic idea are 110 various features which will be referred to in

detail. In carrying out this idea certain dominant features are present. For instance, the actual threaded connection of cap and clamping member is limited circumferentially of the cap, thus dispensing with any requirement of the use of metallic member between the cap skirt and shell, while enabling the use of a clamping member of ample size and cross-sectional area as to efficiently dissipate the heat and thus provide a minimum damaging effect on the threads; another phase of this heat dissipation is the use of the cap as one of the clamping members so that the current need not reach the cap through the threaded connection and the heat dissipation can extend into the cap (through the metallic contact of the parts) independent of such threaded engagement. The arrangement may permit of limited relative movement of the unit in the direction of length of the shell; it may also have means for placing the fusible element under tension; or the unit may be held from movement relative to the shell and the latter may also be threaded to the shell.

In the drawings 20 indicates the shell formed of suitable insulating material, and which may be provided with threaded ends, as in Fig. 6, but which is preferably free from threading as in the remaining views. 21 designates the cap which may be of any of the well-known types, two of which are shown in the drawings. 22 designates the inner clamping member, and 23 designates the fusible element, shown as in strip form but which obviously could be in wire form.

As shown, member 22, in each case is formed to engage threads on the interior of the cap skirt, and at the same time is so mounted with respect to the shell as to be free from complete rotational movement in the shell, the parts being arranged so as to prevent such rotational movement, as in Figs. 5 to 9, or having a limited movement in this direction as in Figs. 1 to 4, it being understood that the clamping members of Figs. 7 and 8 may be used in connection with the shells of Figs. 1 to 4, in which case such limited movement would be provided, such limited movement permitting adjustment of the blades to a limited extent without affecting clamping action on the fusible element. Similarly, the unit may have a limited longitudinal movement in the shell, as in Fig. 1 or such movement may be prevented, as in Fig. 7, these movements being dependent on the particular form of openings 20^a formed in the shell.

Member 22 may have different forms. 60 For instance, in Figs. 1 to 3, 7 and 8, the member is shown somewhat H-shaped, the inner elongated portion being adapted to extend into or through openings 20^a, the outer elongated portion resting on the end 65 of the shell, the outer portion having the

clamping surface which opposes the cap, the inner portion acting to retain the cap against withdrawal from the shell excepting by a threading action. Either elongated portion may carry the thread-engaging structure, 70 which may be in the form of a single thread or a plurality of threads. In Fig. 1 the outer portion is shown as threaded, while in Fig. 2, the inner portion carries the threads; both show a plurality of threads, while in 75 Figs. 7 to 9, the engagement is by a single thread carried by the inner portion. The member may be enlarged at the threaded portion, as in Fig. 1, or on the clamping surface, as in Figs. 2 and 8, but a preferred 80 arrangement of this type of member is that shown in Figs. 7, 9 and 10, in which it is shown as stamped out in completed form thus eliminating any requirement of a machining operation. The structure of Figs. 85 8 and 11 may also be stamped out and then bent over to form the extended clamping surface. The cap is threaded complementary to the particular form of member employed, that shown in Figs. 7 to 9 being of coarse 90 threads to accord with the single thread of the structure of Fig. 10, this arrangement being especially desirable by reason of its quick action, a single turn of the cap being generally sufficient to remove the cap or 95 place it in clamping position.

Member 22 is placed in position before the cap is positioned, remaining in position, the member being inserted internally of the end of the shell to permit the inner elongated portion to pass into openings 20^a. If desired, the member may be especially formed to aid in such inserting movement by shifting the cross-connection as in Fig. 3.

In Fig. 4, the member 22 is shown with 105 the outer elongated portion omitted, the body portion projecting outwardly to form the clamping surface. In this form I preferably arrange the member in two parts, connected together, as by a screw 24, to permit ready positioning of the member in the shell, it being understood that during the refilling action this screw is not disturbed. In Figs. 5 and 6, member 22 also has the outer elongated portion omitted, the member 110 being integral in structure, the member being located in slots 20^b extending inwardly from the ends of the shell, instead of openings 20^a spaced from such ends. As this latter arrangement does not provide engagement between the member and shell, I produce this result in other ways. For instance, in Fig. 5 I have shown the skirt of the cap 115 as carrying pins 25 adapted to extend into the openings 20^a, these pins being carried, for example, by screws; in Fig. 6, I have shown the shell as threaded to correspond with the threads of the member. In each instance, however, the cap is held from withdrawal excepting by a threaded action.

As will be understood, the openings 20^a or slots 20^b are arranged diametrically opposite and are of similar form. This permits of ready formation by the use of suitable mechanism which enables the aligned openings or slots of an end to be placed in position at one operation, thus materially reducing the cost, threading being eliminated excepting in the form of Fig. 6, an operation

10 of considerably greater expense.

If desired, member 22 shown in Figs. 8 and 11 may be formed with a slot 22^b through which the fusible element may pass, but this is not essential, Fig. 8 showing the 15 manner in which the fusible element can be placed in position either within the slot or out of such slot.

If desired, I may also employ means for placing the fusible element under tension, 20 using a spring mounted externally of the shell between the skirt of the cap and an annular member 27, the latter preferably carrying securing members 27^a. This arrangement is especially useful where openings 20^a are elongated lengthwise of the shell, thus permitting longitudinal movement of the unit formed by the cap, member 22 and the clamped portion of the fusible element; this permits the fuse to act as 25 an indicating fuse. Where this arrangement is employed, the spring 26 and member 27 are moved toward the opposite end of the shell and the fusible element placed in clamped position with member 22 having 30 the projecting portions of the inner elongated portion positioned at the inner end of openings 20^a. The spring and member 27 are then moved to position to compress spring 26 and member 27 secured in place. The 35 clamping action on the fusible element prevents spring 26 becoming active until the fusible element has been sufficiently weakened, whereupon the spring will forcibly move the unit outwardly a distance equal 40 to the travel of member 22 in slots 20^b. Such movement of the cap would carry with it the inner member which limits the length of movement excepting in Fig. 5 in which the cap carries the movement-limiting 45 means. This tension action also serves to aid in preventing explosions, in that it tends to disrupt the fusible element before it reaches its melting point.

As will be readily understood, the only 50 action required during the refilling operation is to remove the caps, insert a new fusible element, and restore the caps to position, the inner members 22 retaining their positions. No material manipulation with tools 55 is required. The parts are mainly inclosed by the caps, excepting where the arrangement of Fig. 5 or the tensioning structure is employed. The inner member 22 may be 60 in bar or plate form, to more readily conform to the requirements of openings 20^a

which need not be an accurate configuration with the bar, movement rotationally being permitted, if desired, within limited amounts to permit alinement of fuse blades. However, it may be desirable to prevent such 70 rotational movement, especially with respect to the blade type of fuse, thus limiting the fuse to predetermined thicknesses of fusible elements.

This latter effect will be understood from 75 Figs. 9 and 12. Where the fusible element is of proper thickness both caps, when threaded to position will present their blades on the same plane (represented by line *a* in Fig. 12), thus placing the blades in proper 80 position to enter the fuse-block. If, however, the fusible element be of an increased thickness, neither cap can be threaded sufficiently to bring the blades into alinement (see lines *b* and *c* of Fig. 12), thus preventing 85 entrance of the fuse into the fuse block. A similar result will accrue if the thickness be decreased below that intended, the threading action carrying the caps beyond blade alining position. In either case, indication 90 would be given of the wrong size fusible element being employed, while in the first case use of the increased thickness would be prevented. Where play is permitted, the limited movement would not affect the 95 clamping action as the movement would be of the entire unit.

As will be clear, a positive clamping action is provided and maintained regardless 100 of any contracting or expansion effect which may be had by the shell, especially when made of fiber; this is due to the fact that the cap and member 22 are threaded together, so that contraction of shell is ineffective, even in the form shown in Fig. 6. In 105 addition, conducting relation is not only had through the threaded connection but is mainly provided through direct contact of fusible element and cap, thus relieving the threaded connection from damaging effects 110 due to metallic contact. And where the form of Figs. 7 to 9 is employed, this effect is still further reduced by reason of the small amount of surface contact in the threaded 115 engagement.

While I have herein shown and described various ways in which my invention may be carried into effect, it will be obvious that other changes and modifications may be desired or required to meet the exigencies of 120 use, and I desire to be understood as reserving the right to make such changes and modifications as may be found necessary in so far as the same may fall within the spirit and scope of the invention as expressed in 125 the accompanying claims.

Having thus described my invention, what I claim as new is:

1. In a refillable fuse, a shell, and a fusible-element clamping unit comprising an 130

end cap and a member within and threaded to the skirt of the cap at spaced points circumferentially of the interior of the skirt.

2. In a refillable fuse, a shell, and a fusible-element clamping unit comprising an end cap and a sheet metal member within and threaded to the skirt of the cap at spaced points circumferentially of the interior of the skirt.

10 3. In a refillable fuse, a shell, and a fusible-element clamping unit comprising an end cap and stamped-out sheet metal member within and threaded to the skirt of the cap at spaced points circumferentially of the interior of the skirt.

4. In a refillable fuse, a shell, and a fusible-element clamping unit comprising an end cap and a member within and threaded to the skirt of the cap, said unit and shell 20 having coöperating means for retaining said member against complete rotational movements.

5. In a refillable fuse, a shell, and a fusible-element clamping unit comprising an end cap and a member within and threaded to the skirt of the cap, said unit and shell 25 having coöperating means to permit limited relative movement lengthwise of the shell.

6. In a refillable fuse, a shell, a fusible-30 element clamping unit comprising an end cap and a member within and threaded to the skirt of the cap, said shell and unit having a limited relative movement lengthwise of the shell, and means coöperating 35 with the cap for placing the fusible element under tension.

7. In a refillable fuse, a shell, a fusible-element clamping unit including a metallic end-cap, and tension means carried by and 40 external of the shell and coöperating with the cap for placing the fusible element under tension.

8. In a refillable fuse, a shell, a fusible-element clamping unit including a metallic 45 end-cap, an annulus external of and adjustable lengthwise of the shell, and a compression spring between said cap and annulus.

9. In a refillable fuse, a shell, and a fusible-element clamping unit comprising 50 inner and outer members with the inner member threaded to the skirt of the outer member, said shell and one of said clamping members having coöperating means to permit limited endwise movement of the unit 55 relative to the shell.

10. In a refillable fuse, a shell, a fusible-element clamping unit comprising an end cap and a member within and removably

secured to the skirt of the cap at spaced points circumferentially of the interior of the cap.

11. In a refillable fuse, a shell, and a fusible-element clamping unit comprising an end cap and a member within and threaded to the skirt of the cap, said shell being 60 slotted, said member having projecting portions entering said slots.

12. In a refillable fuse, a slotted shell, and a fusible element clamping unit comprising an end cap and a member within said cap 70 and having projecting portions entering said slots, said portions being threaded to the skirt of the cap.

13. In a refillable fuse, a shell, and a fusible-element clamping unit comprising an 75 internally-threaded end cap, and a member having spaced-apart portions adapted to engage a single thread of the cap.

14. In a refillable fuse, a shell, and a fusible-element clamping unit comprising an 80 internally-threaded end cap, and a substantially flat member having teeth adapted to engage threads of the cap.

15. A fusible-element clamping member 85 formed of sheet metal and having toothed portions adapted to engage the threads of an end-cap.

16. A fusible-element clamping member 90 formed of sheet metal and having toothed portions spaced from the clamping face.

17. A sheet-metal fusible-element clamping member of uniform thickness and having toothed projecting portions.

18. In a refillable fuse, a shell, and fusible-element clamping units at opposite ends of 95 the shell, each unit comprising an end-cap positionable by a threading movement, and a member within and to which the cap is threaded at spaced points circumferentially of the interior of the cap.

19. In a refillable fuse, a shell, and fusible-element clamping-units at each end of the shell, each unit including an end-cap carrying a contact blade, and a member positioned within and threaded to the skirt of the cap, 100 said caps and members being relatively positioned to limit threading movements of the end-caps to place the blades in alinement solely in the presence of a fusible element of predetermined size.

In testimony whereof, I have affixed my signature in the presence of two witnesses.

ALBERT F. DAUM.
